PAGE 3

Fig. 4.

Fig. 5.

Fig. 1 is a perspective view of a prefabricated bathroom unit embodying my new design as seen from one end with a portion of the wall and ceiling broken away for purposes of illustration;

Fig. 2 is a perspective view thereof as seen from the opposite end with a portion of the ceiling and of the wall broken away for purposes of illustration;

Fig. 3 is a horizontal sectional view thereof taken along the line 3—3 of Fig. 1 in the direction of the arrows;

Fig. 4 is a reduced vertical sectional view thereof taken on line 4—4 of Fig. 3 and in the direction of the arrows;

Fig. 5 is a reduced vertical sectional view of the same taken on line 5—5 of Fig. 3 and in the direction of the arrows.

I claim:

The ornamental design for a prefabricated bathroom unit, as shown.
